PORTABLE TRAFFIC SIGNAL

William Talmadge Hall, Jr., 11 Northbriar Drive,
North Kingstown, R.I. 02905

Filed Dec. 12, 1973, Ser. No. 423,905

Term of patent 14 years

Int. Cl. D29—02

U.S. Cl. D10—114

FIG. 1

FIG. 2

FIG. 1 is a perspective view, as seen from the front left corner of portable traffic signal, showing my new design;

FIG. 2 is a fragmentary perspective view, as seen from the rear right corner thereof, the wheel and frame being broken away for purposes of disclosure.

I claim:

The ornamental design for a portable traffic signal, as shown and described.
